UNITED STATES PATENT OFFICE.

JOSEPH HINDLEY, OF TYLDERLEY, ENGLAND, ASSIGNOR TO FINE COTTON SPINNERS AND DOUBLERS ASSOCIATION LIMITED, OF MANCHESTER, ENGLAND.

MACHINE FOR COMBING COTTON AND OTHER FIBERS.

1,245,919.

Specification of Letters Patent.

Patented Nov. 6, 1917.

Application filed March 2, 1916. Serial No. 81,691.

To all whom it may concern:

Be it known that I, JOSEPH HINDLEY, a British subject, residing at Tyldesley, county of Lancaster, England, have invented certain new and useful Improvements in Machines for Combing Cotton and other Fibers, of which the following is a specification.

This invention relates to combers for cotton and other fibers in which the lap is detached or broken and the fibers combed by a revolving cylinder and a top comb such as the Heilmann, Nasmith, Delette and Gegauff combers.

The purpose of this invention is to subject the rear ends of the fibers to the combing action of the cylinder in addition to that of the top comb after the lap has been detached or broken and before being pieced up again.

To effect this I increase the number of rows of needles on the cylinder bringing them nearer to the fluted segment at both edges, alter the design of the quadrant cam to return the rear ends of the fibers into the cylinder needles and then draw them forward again preparatory to piecing, alter the lifter cam to bring the nip of the detaching rollers nearer to the cylinder, also the design of the side cam which opens and closes the quadrant clutch on the detaching roller to suit the altered design of the quadrant cam and give a longer over lap when piecing and also alter the angle of the front of the top comb and attach the needles to the front instead of to the back to get a greater length of the rear end of the fibers through the needles.

The invention will be fully described with reference to the accompanying drawings.

Figure 1 is a transverse section through the comber head.

Fig. 2 is a front elevation of the quadrant cam.

Fig. 3 is a perspective view of the side cam.

Fig. 4 is a view of the lifter cam.

Fig. 5 is a perspective view of the quadrant cam D, the side cam and the quadrant and clutch lever working therewith.

The cylinder A is constructed with a greater number of rows of needles *a* than ordinarily and these are extended both forward and backward to bring them nearer or closer to both edges of the ordinary fluted segment *a'*.

The detaching rollers B B' are mounted in the ordinary way over the cylinder A; and the quadrant cam D by which they are actuated is designed as shown to give four distinct or separate movements to the quadrant E and roller B:

(a) Detaching.

(b) Returning the rear ends of the fibers into the cylinder needles after the dirty needles have passed the detaching rollers.

(c) Drawing the fibers forward slightly to clear the tail ends from the cylinder needles.

(d) Returning the fibers for piecing purposes.

The bowl *e* (Fig. 2) on the end of the quadrant E engages in the usual way with the cam D. The bowl *e* is at the point *d* of the cam when detaching commences and travels from *d* to *d'* during the operation of detaching. When the point *d'* is reached the rotation of the roller B is stopped by the opening of the clutch F. During the time the clutch F is out of gear and the roller B is stopped the bowl *e* travels from *d'* to *d''*. When the point *d''* has been reached by the bowl *e* the clutch F closes, the roller B is reversed, and during the travel from *d''* to *d'''* the rear ends of the fibers are returned into the cylinder needles to be combed (as shown in Fig. 1). When the point *d'''* has been reached the roller B is turned forward again and the fibers are drawn forward through the cylinder pins during the travel from *d'''* to *d''''*. When the point *d''''* has been reached the fibers are again returned for piecing during the travel from *d''''* to *d*, and at the point *d* the detaching of the next length of fibers commences.

The side cam G, by which the clutch lever F' that controls the clutch F is actuated is shaped at *g* to keep the clutch open while the quadrant bowl *e* travels from *d'* to *d''* on the cam D.

The lifter cam H by which the detaching rollers are raised and lowered is preferably reduced in diameter in the concentric part and so shaped as not to remove the leather roller C more than $\frac{3}{2}$ of an inch from the cylinder needles to obtain a closer grip of the fibers while being combed.

The blade of the top comb K is beveled at the front and straight at the back and the needles are affixed to the beveled front of the blade instead of to the back as usually

done thereby permitting the blade to be set more nearly vertical while retaining the requisite angle of the needles, and the needles to be set more closely to the detaching 5 rollers thereby enabling a greater length (up to a full $\frac{1}{4}$ " longer length) of the rear ends of fibers to pass through and be combed by the top comb.

By this construction the rear ends of the 10 fibers after being detached are returned into the cylinder needles and are combed by the finer needles which have accumulated the least amount of waste and dirt from the lap.

15 What I claim as my invention and desire to protect by Letters Patent is:—

1. In a comber of the type described, the combination, with a top comb, and a combing cylinder having main and excess or supplemental rows of needles thereon; of detaching rollers co-operative therewith; a quadrant for actuating one of said rollers; and a quadrant cam operatively connected with said quadrant and constructed to successively impart four distinct or separate movements to said quadrant and its associated roller, so as to cause the rollers to successively detach the fibers, return the rear ends of the fibers into the cylinder after 25 the main needles have passed said rollers to

be acted upon by the excess or supplemental needles, draw the fibers slightly forward to clear their said rear ends from the cylinder needles, and return the fibers for piecing purposes.

2. In a comber of the type described, the combination of a combing cylinder having main and excess or supplemental rows of needles thereon; a top comb having a beveled front face to which its needles are attached; detaching rollers co-operative with said cylinder and top comb; and a cam operatively connected with said detaching rollers and constructed to cause the same to detach the fibers, return the rear ends of the fibers into the cylinder after the main needles have passed said rollers to be acted upon by the excess or supplemental needles, draw the fibers slightly forward to clear their said rear ends from the cylinder needles, and return the fibers for piecing purposes.

35 Dated the 3rd day of February, 1916.

In testimony whereof I have hereunto set my hand in presence of two subscribing 40 witnesses.

JOSEPH HINDLEY.
